Primary Examiner — Cathron C Brooks*(74) Attorney, Agent, or Firm* — Schwegman Lundberg & Woessner, P.A.**CLAIM**

The ornamental design for an assembled modular closet cabinet, as shown and described.

DESCRIPTION

FIG. 1 is a perspective view of an assembled modular closet cabinet showing my design according to a first embodiment;

FIG. 2 is a front view thereof;

FIG. 3 is a rear view thereof;

FIG. 4 is a left view thereof;

FIG. 5 is a right view thereof;

FIG. 6 is a top view thereof; and

FIG. 7 is a bottom view thereof.

FIG. 8 is a perspective view of an assembled modular closet cabinet showing my new design according to a second embodiment;

FIG. 9 is a front view of the assembled modular closet cabinet of FIG. 8;

FIG. 10 is a rear view of the assembled modular closet cabinet of FIG. 8;

FIG. 11 is a left view of the assembled modular closet cabinet of FIG. 8;

FIG. 12 is a right view of the assembled modular closet cabinet of FIG. 8;

FIG. 13 is a top view of the assembled modular closet cabinet of FIG. 8; and,

FIG. 14 is a bottom view of the assembled modular closet cabinet of FIG. 8.
